INDEPENDENT NEEDLE KNITTING MACHINE

Albert E. Page, Brooklyn, N. Y., assignor to Scott
& Williams, Incorporated, New York, N. Y., a
corporation of Massachusetts

Application October 12, 1937, Serial No. 168,645

8 Claims. (Cl. 66—25)

This invention relates to independent needle knitting machines, and more specifically to a machine adapted to make patterned fabric by stitch variation. One of the objects of the invention is to produce a simplified mechanism for knitting patterned fabric such as underwear or outerwear. Another object is to produce a simplified "memory" device for a multi-feed circular knitting machine. It is characteristic of the invention that the needles have sliding butts which are used to give selectivity.

This application contains claims directed to the needle in combination with certain other features, while the needle alone is claimed in my divisional application Serial No. 202,559, filed April 16, 1938.

While the invention will be shown and described embodied in a multi-feed, independent latch needle, circular, rib knitting machine, it should be understood that the invention is applicable to rib or plain, circular or straight machines, and to either rib or plain needles or both, provided always that the needles are independent ones.

In the drawings,

Fig. 1 is a simplified front elevation of a multi-feed, independent needle, rib knitting machine, in which the present invention has been embodied in the dial;

Fig. 2 is a view in elevation from the right side of the machine, taken on the line 2—2 of Fig. 4, showing in detail the mechanism for moving certain of the dial cams to and from plain knitting position when making a tuck and float stitch pattern, such as shown in Fig. 12;

Fig. 3 is a perspective view on an enlarged scale, showing the manner in which the sliding butt is mounted in the needle;

Fig. 4 is a plan view of a section of the sliding control ring for moving the dial needle cams of Figs. 2 and 12;

Fig. 5 is a view in side elevation of an electro-mechanical hammer suitable for selecting the sliding butts of the needles;

Figs. 6 to 10 are views in vertical section through the outer edge of the dial, taken on the lines 6—6, etc. of Fig. 12; Fig. 6 showing the dial needle in selecting position just after the sliding butt has been pushed down by the selecting hammer; Fig. 7 showing a selected needle projected to tuck position to take yarn, the dotted position of the sliding butt illustrating its position when not selected; Fig. 8 showing how the needles whose sliding butts have not been pushed down are pulled radially inward to miss the yarn after

all the dial needles held the fabric down as the cylinder needles rose; Fig. 9 showing the selected needles at the knocking-over point; and Fig. 10 showing a selected needle pushed out to its clearing position with its sliding butt cammed upward by the edge of the groove in the dial;

Fig. 11 is a development of the cylinder needle knitting cams for one feed of the machine, this feed corresponding to the feed marked "11" in Fig. 12;

Fig. 12 is a plan view of the dial cams and needles for some of the feeds of the machine of Fig. 1 when that machine is adjusted to make tuck and float stitch patterns; the illustrative needles shown in dot-and-dash lines making float stitches and the solid needles making tuck stitches at the pattern feeds;

Fig. 13 is a plan view similar to Fig. 12, showing the dial cams and needles at a majority of feeds of the machine when adjusted to make a tuck and plain pattern;

Fig. 14 is a vertical section through the outer portion of the dial at feed 2, taken on the line 14—14 of Fig. 13, showing a dial needle in solid lines in the yarn-taking position and a dotted needle in the clearing position for this feed;

Fig. 15 is a plan view similar to Figs. 12 and 13, showing dial cams and needles of the machine when adjusted to make a float and plain pattern;

Fig. 16 is a view in radial vertical section through a modified form of means of selecting needle butts, the selecting being done by a trick wheel;

Fig. 17 is a view in elevation looking radially inward, with the edge of the dial cut off, showing a detail of the operation of the trick wheel of the modification of Fig. 16, the arrows representing the direction of movement of the dial and the trick wheel and gear; while

Fig. 18 is a perspective view of the sliding butt needle.

One of the problems in the modern knitting machine, and particularly the multi-feed circular knitting machine, is to find room for all the patterning mechanism which is necessary to produce the desired fabric. One general type of mechanism for accomplishing this end is the so-called "memory" device, in which selecting means are not required at a following feed in order to change the stitch there. The present invention is shown embodied in a "memory" device, but it should be understood that, broadly speaking—and particularly with reference to the needle itself—the invention is not limited to this particular class of device. The present invention

has the great advantage of simplicity in that the selecting means are enabled to act directly on the needle without the intervention of jacks or other elements. In the drawings the invention is shown embodied in the dial and dial needles of a revolving needle cylinder, multi-feed, underwear machine. The machine is a rib machine with the variations in the rib stitches at the first, second, third, fifth, sixth and seventh feeds. While the manipulation of the dial needle hook from one feed to another is varied by having two butts on each needle, it should be understood that a certain amount of patterning is obtainable in accordance with this invention with only one butt on each needle.

Referring now to the drawings, the needle 19 which is shown in Fig. 18 has the usual hook 20 with a pivoted latch 21 and a shank 22. Intermediate the length of the shank is a low operating butt 23 projecting laterally from the shank in the plane of the hook. As the needle lies in the dial with its hook turned upwardly, the fixed butt also lies on the upper side. This butt is of considerable width in order that the novel butt 25 to be described may project through it. The dial 24 has slots 25 to receive the needles. The low fixed butts 23 project above the slots 25 of the dial, as shown in Fig. 17. In the embodiment shown in the drawings this fixed or low butt on the needle is so associated with operating cam paths as to manipulate the needle for the making of plain stitches. It can, of course, be located at any desired point along the length of the shank.

35 The novel needle has a vertically movable high butt 26 adapted to slide vertically in a slot 27 cut in one side of the shank of the needle. Preferably this slot is cut in the low butt 23 because of the simplification of the operating cam paths which is obtained. The slot is equal in thickness to only half the thickness of the shank, as can be seen in Figs. 3 and 18. The sliding butt 26 can be mounted in the shank in a frictioned manner. In the drawings the frictioning means shown comprise a small spring finger 28 riveted to one side of the low butt 23, overlying the slot and pressing against the sliding butt, as shown for instance in Figs. 3 and 18. The two corners of the upper end of the sliding butt 26 may be cut square, but the lower end is preferably rounded. The length of the butt is such that it may project below the shank of the needle or above the low butt of the needle. When it is projected above the low butt, it is adapted, in cooperation with certain cams to be described, to cause special manipulation of the needle.

It has been found possible to cause all the necessary movements of the sliding butt without rocking the needle or otherwise disturbing its longitudinal or knitting operation. While the sliding butt is moved downwardly by the selecting means, it is moved upwardly automatically by the particular shape and form of the dial taken in connection with the longitudinal movement of the needle. To achieve this, a groove or depression 29 is cut in the dial 24, as shown for instance in Figs. 6 to 10, this depression or groove 29 being adapted to underlie the butts 26 except when the needle is in extreme clearing position. As can be seen in Fig. 9, the inner edge of this groove 29, which extends all the way around the upper face of the dial, is such a distance from the center of the machine that when a needle is completely retracted the depression is still underneath the sliding butt. The depression is of such

a depth that when the sliding butt is pushed downwardly till its upper end is flush with the top of the low butt, the lower or rounded end of the sliding butt will not contact with the bottom of the depression (see Fig. 9). As mentioned above, the pushing upwardly of the sliding butt is obtained automatically without reference to the selecting means, by pushing the needle radially outward and causing the sliding butt to ride up the bevelled outer edge 30 of the groove 10 to the position shown in Fig. 10. By the time the sliding butt has climbed out of the groove, as shown in this figure, the needle has been extended to the point where it is clear of the loops which were in the hook. Since the sliding butt 15 is frictioned, it will stay in that uppermost position unless and until it is depressed by some selecting means at a subsequent feed.

The knitting cams for operating on the low butt 23 of the needle will be described next. In 20 the embodiment shown in Figs. 12, 13 and 14, there have been shown, respectively, cam paths adapted to make tuck and float patterns, tuck and plain patterns, and float and plain patterns. These various species of patterning are made to 25 occur at three feeds followed by a fourth feed at which all needles knit plain stitches, i. e., knit off the tucks.

I will first describe the cams and needle movements in Fig. 15 where the pattern feeds 30 make float or plain stitches according to the selection made among the high or sliding butts by the selecting mechanism. In Figs. 12, 13 and 15, the dial knitting or knocking-over cams are designated by the numeral 31 at each feed, six such 35 cams being shown at Fig. 15, out of the eight in the machine. In Fig. 15 only one clearing cam is shown in its entirety, this being the cam designated by the numeral 32 and preceding the second knitting cam counting from the top of the 40 drawing in a clockwise direction. The counterclockwise arrow at the top of this figure indicates the direction of movement of the needles through the cams, and this figure will serve as an explanation of either a stationary needle cylinder or a 45 stationary dial machine. The knitting cams 31 immediately succeeding the two clearing cams 32 in a counterclockwise direction therefore are the knitting points for the plain feeds. In the following explanation of the operation of the machine, these plain feeds will be designated as 4 and 8. The feeds immediately following them in a counterclockwise or knitting direction will be designated as 5 and 6, respectively. When a dial needle is pushed all the way out to clear position by one of the clearing cams 32 at feed 4 or 8, it assumes the position shown in Fig. 10. It will be noted that it reaches this position by virtue of the low or fixed butt 23 and not the high butt 26.

The sequence of movement of the needles in Fig. 15 will now be followed, beginning immediately after the needles leave the knitting cam 31 at feed 8 at the lower left hand corner of the figure. The pushout cam 33 pushes the needle 65 radially outward after it leaves the knitting point until it reaches the selecting point shown in Fig. 6. At this point the sliding butt 26 passes under a selecting member or hammer 34 which will depress the sliding butts of selected needles 70 in accordance with the pattern requirements. If the sliding butt is depressed it assumes the solid line position shown in Fig. 6; if it is not depressed it remains in the dotted line position in that figure. The pushout cam 33 continues to 75

push the needle radially outward by contacting the low butt 23 until the needle assumes the tuck position shown in Fig. 7. One purpose of pushing the needles out to this position at this point is to assist in holding the fabric down on the cylinder needles 84 which are beginning to rise on cam 85 (Fig. 11). There is a cam 35 lying radially outside the butt, as shown in Fig. 15, and shortly after reaching the position of Fig. 7 this cam 35 pushes all needles inward to a point where they will miss the yarn. The needles with elevated butts are at once brought out to the clearing point by a cam 37. After this point they take the yarn. The cam 37, however, is undercut and does not push out the butt-depressed needles. They make float stitches. All the needles are then drawn down at the knitting point by cam 31 of feed 1 and the needles with elevated butts knit while those with depressed butts make float stitches. The same sequence of operation occurs at feeds 2 and 3. Entering feed 4, as the needles leave the stitch cam 31 of feed 3 they are raised or pushed radially outward by pushout cam 33 of feed 4. Instead of cam 35, there is a cam 38 which has no overhanging portion to push needles radially inward, so that all the needles take yarn, are cleared by the cam 32 and knit at the knitting cam 31 of the fourth feed. The entire series of operations is repeated at feeds 5, 6, 7 and 8.

The sliding butts, after being depressed, must again be elevated automatically as above mentioned, before reselection can take place between the fourth and fifth feeds. Therefore the clearing cam 32 at feed 4 moves the needles out still further than the clearing cams 37 at feeds 1, 2 and 3. This causes the sliding butts to rise up the bevel 30 and assume the position shown in Fig. 10.

If it is desired to substitute tuck stitches for the float stitches, the cam arrangement is that shown in Fig. 13. The knitting cams 31 and the pushout cam 33 are unchanged, but there is a new push-in or guard cam 39 and a new clearing cam 40 to take the place of the clearing cam 37 at feeds 1, 2 and 3, and a clearing cam 41 of a different shape at feed 4. The only undercut cams are the clearing cams 40 at feeds 1, 2 and 3, all needles being treated alike by all the other cams. With this construction all the needles are pushed out by the regular push-out cam 33 to a tuck position and are held in approximately this position by the guard cam 39. All take yarn. The needles whose sliding butts were not depressed will thereafter be cleared by the clearing cam 40, but those needles whose sliding butts were depressed will pass through the undercut 42 of the cam 40 and will not be cleared. The needles with depressed sliding butts therefore will tuck at the knitting point on feed 1. The other needles will knit. The same sequence of operations occurs at feeds 2 and 3. At the fourth feed all needles are cleared and knit. As in the case of the float and plain patterns, feeds 5 to 8 are a repetition of feeds 1 to 4.

We next come to the tuck and float pattern shown in Fig. 12. In the construction shown in this drawing, means are shown for changing the knitting at feeds 1, 2, 3, 5, 6 and 7 to plain stitches (the knitting at feeds 4 and 8 always plain stitches). However, I will first describe the cam arrangements which make it possible to make tuck and float patterns at feeds 1, 2 and 3. The knitting cams 31 and the regular pushout cams 33 of the constructions of Figs. 13

and 15 are retained in the tuck and float setup of Fig. 12, but a new push-in cam 35' and a new clearing cam 43 are provided at each of feeds 1, 2 and 3. The push-in cam 35' has a point adapted to push needles inward after they ride off the push-out cam 33, this point being undercut at 36 so that only those needles whose sliding butts are up will be pushed in. The needles whose butts are depressed will pass through the undercut to take the yarn but they tuck rather than knit when they reach the next hitting cam 31. The needles with elevated butts that are pushed in, as above-mentioned, do not take yarn and therefore make float stitch at each of feeds 1, 2 and 3. At feed 4, instead of the push-in cam 35' there is a guard cam 38 which holds all the needles at the tuck position and there is a special clearing cam 44 which pushes all needles out to take yarn and clear at this feed, the needles being pushed out to the position of Fig. 10, as in both constructions above described. The clearing cams 43 at feeds 1, 2 and 3 are each pivoted at a point 45 and when swung in a clockwise direction about this pivot they move out to clearing position though not far enough to cause any depressed sliding butts to be cammed upwardly, as shown in Fig. 10 but rather to the extent shown by the dotted needle in Fig. 14. This movement of the clearing cams 43 is obtained from an oscillating control ring 47 lying on the dial cap just inside the needles, each of the clearing cams 43 at feeds 1, 2 and 3 being pivotally connected to the ring so that its oscillation moves them from one position to the other. Movement in the direction of the clockwise arrow 35 on the ring in Fig. 12 brings these cams to guard position where tuck and float stitches are made, and movement in a counterclockwise direction brings them out to their clearing position where plain stitches are made at all feeds. To bring out the correlation of the dial and cylinder needle movements, the knocking-over point 86 of the cylinder needles and the knocking-over point 87 of the dial needles have been marked in Fig. 12 at the third feed. It is interesting to note that in the tuck and plain pattern and in the float and plain pattern the needles with depressed sliding butts remain radially inward when passing under the undercut cams relatively to the needles whose sliding butts are raised; whereas in the case of the tuck and float patterns the needles with depressed butts remain out relatively to the needles with raised butts. All the plain stitches at feeds 1, 2 and 3 are made by non-depressed needles. 50

The operation of the control ring 47 is caused by a pattern chain 48 racked ahead by a pawl 49 operated from a lug on a ring (not shown) revolving with the needle cylinder. Specifically referring to Figs. 2 and 4, there is a bell crank lever 50 mounted on the frame 51 of the machine and given a rocking movement periodically by the lug on the revolving ring. On the upper end of this bell crank lever 50 is the pawl 49 having a reciprocating movement over a rack wheel 52 65 (Fig. 2). The rack wheel is coaxial and revolving with a sprocket wheel 53 carrying the pattern chain 48 on which are the lugs for causing the control ring movement. The indications of these lugs are transmitted to the control ring 47 70 by a finger 54 in one arm of a bell crank lever 55 held in contact with the lugs on the pattern chain by means of a tension spring 56. The lugs on the chain are indicated at 57 and they are all of the same height, the ring being moved from one 75

extreme position to the other when the finger 54 moves between the surface of the pattern chain and the top of one of the lugs 51. By use of an intermediate ring position the cams 43 can make 5 tuck stitches on all needles. The outer end of the upper arm of the bell crank lever 55 is fastened pivotally to a rod 58 overlying the dial cap 60, the inner end of the rod 58 being pivoted to one arm of a small bell crank 59 pivoted on the 10 dial cap. The other arm of the small bell crank straddles the upper end of a pin 61 carried by the control ring 47 and extending upwardly through the dial cap 60. The parts are shown in their 15 guarding or non-clearing position in Figs. 2 and 4, as well as in Fig. 12. The arrows in Fig. 4 indicate the direction of movement of the parts when going to clearing position, the dotted position of the needle cam 43 being in idle or guard position, and the dot-and-dash outline showing the 20 cam in its clearing position. Any other suitable form of pattern control can be employed for actuating this ring at the properly timed intervals.

Any suitable form of selecting the sliding butt 25 26 can be employed. In the drawings I have shown two forms. In Figs. 1 and 5 is shown a form of electro-mechanical selection of the general type shown in the Albert E. Page application Serial No. 137,106, filed April 15, 1937. In 30 Figs. 16 and 17 is shown a trick wheel construction for selecting the butts. Another type of device which would be suitable for this work is an endless paper or metal sheet with holes punched therein which could be passed over the 35 butts and thus push down those where there were no perforations. I will describe in general terms the electro-mechanical mechanism shown diagrammatically in Figs. 1 and 5. As shown in Fig. 5, the selecting element which acts directly 40 on the high butt 26 of the needles is a pivoted hammer 34 carried by a frame which is mounted non-revolvally on the collar carrying the dial cap 60. This frame 62 can be of metal and one part of it can be used as a core for an electro-magnet 45 63. This electro-magnet is close to the back end of the pivoted hammer 34 and when energized this coil will attract the back end of the hammer and cause the high butt below the other end of the hammer to be depressed. A tension spring 50 64 tends to keep the hammer in its upper position where the butts of the needles are not acted on.

Electric impulses properly synchronized with the revolutions of the needle cylinder to select 55 any desired needles by pressing down their high butts, are obtained from a vertical drum 65 above the needle cylinder, co-axial therewith and revolving in unison with it. This drum bears on its periphery a pattern 66 which can, if desired, be colored so as to create selective impulses in 60 photo-electric cells as beams of light reflected from the pattern surface enter such cells. These cells are indicated in Fig. 1 by the numeral 67. They are circumferentially stationary but move 65 vertically on posts 78 to read the pattern in a spiral corresponding to the individual needles and the stitches in the resulting fabric. Mechanism can be provided to cause each of these cells to reverse its direction at the end of travel, thus 70 reading the pattern first in one direction and then in the other. (In the drawings I have shown two photo-electric cells, one to act on the high butts of the needles just prior to the first feed, and the other to act on the butts just prior to the fifth feed.) In Fig. 1 I have indicated a

suitable driving and reversing mechanism for the vertical movements of the cells. This is operated from a large gear ring 68 mounted on and revolving with the shaft carrying the needle cylinder but located above the bracket supporting the cylinder and the dial cam ring. A train of gears 69, 70, 71 and 72 transmits its movements to reversible bevelled driving gears 73, 74, 75, the clutch element 76 of such reversible gearing being initially actuated in a vertical direction to start the reversing operation by the arrival of the cell at the end of its travel. The vertical travel of the cells is caused by screw threads 77 on the vertical rods 78 carrying these cells.

The trick wheel construction for selecting the 15 needle butts is shown in Figs. 16 and 17. As shown in these two figures, both the low butts 23 and the sliding high butts 26 of the needles project above the dial 24. Advantage of this fact is taken by using a trick wheel 79 mounted on a 20 horizontal axle 80 revolving just above the high butts. There are flat teeth 81 on the periphery of the trick wheel. Wherever there is a tooth on this trick wheel 79 the high butt will be depressed to a position flush with the low or fixed butt 23. 25 Wherever such tooth is cut out, a high butt will remain in its uppermost position, shown for instance in Fig. 16. For the purpose of turning this trick wheel in timed relation with the needles, there is a gear wheel 82 mounted beside the trick 30 wheel and having teeth 83 around its periphery which are slightly longer than those on the trick wheel. The teeth on the gear wheel are offset with relation to the trick wheel teeth so that they will overlap and intermesh with the low butts 23 35 of the needles and the passing of the needles will cause the gear wheel to turn. The trick wheel is turned with its teeth in register with the high butts rather than the spaces between the needles.

The construction of the machine having been 40 described, its operation will now be set forth. Assuming that it is desired to make tuck and float stitch at feeds 1, 2, 3, 5, 6 and 7 by use of the mechanism in Figs. 11 and 12, and getting the selection from the electro-mechanical means of 45 Figs. 1 and 5, the operation is as follows. Wherever in the pattern it is desired that a tuck stitch be made at feeds 1, 2 and 3, the pattern 67 is so colored as to cause the photo-electric cell to transmit an electric impulse to the electro-magnet 63, thereby causing the hammer or selecting element 34 to push down the sliding high butt 50 26 of the needle corresponding to that point in the pattern. This depression takes place at the bottom of Fig. 12 where the lower end of the 55 hammer 34 is indicated in cross-section. The position of the dial and cylinder needles at this moment of selection is shown at Fig. 6. It will be noted that the upper end of the sliding butt of the dial needle is now flush with the top of the fixed low butt 23. The lower end of each 60 sliding butt rests in its groove 29 in the dial 24. The pushout cam 33 moves the dial needle radially outward to tuck position, which is the position shown in Fig. 7 and at line 1-7 of Fig. 12. It will be noted that this pushout cam, in causing 65 this movement, is in contact with the low fixed butt 23 and that therefore all the needles are brought out to this tuck position. The continued revolution of the dial brings the needles opposite the guard cam 35' which is undercut at 36, at such a level as to permit the needles whose high butts have been depressed to pass under the cut 36, but the needles whose butts are still raised are forced radially inward to the dotted position 70 75

shown in Fig. 8 and the line 8-8 of Fig. 12. In the meantime, after the dial needles reached the position of Fig. 7 the cylinder needles rose up their clearing cam 85 and the dial needles acted 5 to hold the fabric down to assist in clearing the latches of the cylinder needles. The needles with butts depressed, after they pass the undercut 36, take the yarn at feed 1, but the needles with butts not depressed are pushed in radially to miss 10 the yarn. These latter needles travel along on swivel cam 43 and the next pushout cam 33 at the knocking-over point without coming out again or taking any yarn. In the meantime the tuck needles with butts depressed have gone into 15 contact with knitting cam 31 at the first feed and are drawn in, but since the latch was not cleared the needle does not knit. The action of the needles at feeds 2 and 3 is identical with that 20 of feed 1.

At feed 4, after all the needles have been pushed out by cam 33 they are all allowed to stay 25 out at the tucking position by cam 38 which replaces cam 35, and all the needles take yarn. Instead of the swivel cam 43 at this feed there 30 is a clearing cam 44 which clears all the needles by engagement with their low butts 23, thus pushing the needles radially outward to the position shown in Fig. 10. It will be noted that by pushing these needles out to the clearing position 35 shown in Fig. 10, the lower end of the sliding butt contacts the outer end 30 of the groove 29 and the sliding butt is thereby cammed upwardly into position for reselection. There is no frictional jamming of the needles by this resetting 40 of the sliding butt because the clearing cam 44 is acting on the fixed or lower butt while the edge 30 of the groove 29 is acting on the sliding butt only, and should a butt be only partly depressed there will be no jamming. The sequence of operations at feeds 5 to 8 is the same as at feeds 45 1 to 4.

When it is desired to knit plain stitches at feeds 1, 2 and 3 and feeds 5, 6 and 7, the pawl 49 turns the rack wheel 52 and the sprocket wheel 53 until the finger 54 drops off the lug 57 on the pattern chain 48 and the large bell crank lever 55 actuates the small bell crank 60 and moves the control ring 47 in a counter-clockwise direction, as appears in Fig. 12. This causes the three 50 swivel cams 43 to assume their clearing positions. It will be noted by comparison of Figs. 10 and 14 (Fig. 14 showing the clearing position of the swivel cams 43) that the dial needles are not pushed as far out at feeds 1, 2 and 3 as they are 55 at feed 4 although the needles are cleared at all four feeds. It is necessary to differentiate in the extent to which the needles are pushed out in order that the sliding butts may not be reset until feed 4 is reached.

Turning now to Fig. 13, where the machine is going to make tuck and plain stitches at feeds 1, 2 and 3, and plain stitches only at feed 4, the selection of needles by depressing butts takes place in the same manner as in the case of Fig. 12, but the outer cam 39 does not push the non-depressed butt needles radially inward after they reach the tucking position and all the needles take yarn. The clearing cam 40 which is undercut as shown at Fig. 14, leaves the depressed butt 50 needles at tuck position but pushes out to clear position the needles whose butts have not been depressed. Thereafter the knitting cam 31 operates on all the needles and the needles which have not been cleared make tuck stitches while 55 the needles whose butts have not been depressed

knit plain stitches. At feeds 2 and 3 the operation is the same as at feed 1. At feed 4, instead of the clearing cam 41 being undercut, it is solid and all the needles are pushed out to clear position and knit plain stitches. 5

Referring now to Fig. 15, where float and plain stitches are knit at feeds 1, 2 and 3, all the needles are pushed out to tuck position to hold the fabric down for the cylinder needles but then are pushed in by cam 35 to float position. 10 This occurs before the needles can take yarn. The needles whose butts have not been depressed are then pushed radially outward to the clearing position by a cam 37 to clear, take yarn and thereafter knit at the knitting cam 31, as usual. 15 The depressed butt needles make float stitches. The operation is the same at feeds 2 and 3.

At feed 4 the outer cam 38 does not push any needles radially inward, all needles take yarn, are cleared by the solid clearing cam 32 with resetting 20 of their sliding butts, and all needles knit at the knitting cam 31.

It will be noted that there is no tipping of the shank of the needles which would affect the stitch-making ability of the elements. The jacks 25 or separate knitting instrumentalities for which there is little room in the dial are not required.

Many modifications which do not depart from the scope of my invention will occur to those skilled in the art. 30

What I claim is:

1. A knitting machine having a needle bed and a plurality of independent needles therein having hooks and shanks, one or more of said needles having a butt slidably with relation to the shank of the needle in the plane of the hook of the needle and of sufficient size to project above or below the rest of its needle for selecting purposes, there being a groove in the bed whereby the butt can project below the shank in certain longitudinal positions of the needle but is cammed upwardly when moved to certain other positions and thereby caused to project above the rest of the needle. 35

2. A knitting machine having a needle bed and a plurality of independent needles therein having hooks and shanks, one or more of said needles having a butt slidably with relation to the shank of the needle in the plane of the hook of its needle and of sufficient size to project above or below the rest of the needle for selecting purposes, there being a groove in the bed whereby the butt can project below the shank in certain longitudinal positions of the needle but is cammed upwardly when moved to certain other positions and thereby caused to project above the rest of the needle, in combination with selecting means associated with the bed adapted to push selectively on said butts in the planes of the hooks of the needles. 45

3. A knitting machine having a needle bed and a plurality of independent needles therein having hooks and shanks, a plurality of said needles each having a butt on the shank slidably with relation to the shank in the plane of the hook and adapted to project either above or below the rest of its needle for selecting purposes, there being a groove in the bed whereby a butt that projects below the shank will be cammed up and project above the rest of the needle when the latter is 50 moved to extreme clearing position. 65

4. A knitting machine having a needle bed, a plurality of independent needles therein having hooks, shanks and fixed operating butts, and cams above said needles for giving them longi- 70 75

- tudinal operating movements, in combination with a butt on each of a plurality of said needles slideable with relation to the shank of the needle in the plane of the hook of the needle and of 5 sufficient size to project above or below the rest of the needle for selecting purposes, there being a groove in the bed whereby the butt can project below the shank in certain longitudinal positions of the needle but is cammed upwardly when 10 moved to certain other positions and thereby caused to project above the rest of the needle.
5. A knitting machine having a needle bed, a plurality of independent needles therein having hooks, shanks and fixed operating butts, and cams 15 above said needles for giving them longitudinal operating movements, in combination with a frictioned butt on each of said needles slideable with relation to the shank in the plane of the hook and adapted to project either above or below the rest 20 of the needle for selecting purposes, there being a depression in the bed whereby a butt that projects below the shank will be cammed up and project above the rest of the needle when the latter is moved to clearing position.
25. 6. A knitting machine having a needle bed, a plurality of independent needles therein having hooks, shanks and fixed operating butts, in combination with a butt inside said fixed butt on each of a plurality of needles adapted to slide 30 with relation to the shank and to project beyond the fixed butt in the plane of the hook or to be buried therein, means above the needle bed to select sliding butts by depressing those not wanted to the level of the fixed butts, and cam paths 35 to give the needles different manipulations according to whether they present a high or a low butt.

7. A knitting machine having a needle support, a plurality of independent needles therein having hooks, shanks and fixed operating butts, and a frictioned member passing through the shank of each of a plurality of needles in the planes of the hooks of the needles and adapted to project above or below the rest of the needle as a selecting butt, there being a groove in the needle support whereby the butt can be left flush with the fixed butt on one side of the shank while the 10 needle is in certain longitudinal positions but will be cammed up when the needle moves out to extreme clear position, in combination with a cam path adapted to act on the fixed butts and additional cam surfaces adapted to give special movements to needles whose sliding butts project 15 above the fixed butts, and means to select the sliding butts.

8. A knitting machine having a dial, a plurality of independent needles therein having hooks, 20 shanks and fixed operating butts, and a frictioned member passing through the fixed butt of each of a plurality of needles in the planes of the hooks of the needles and adapted to project above the fixed butt or below the shank as a selecting butt, in combination with means to select from among the sliding butts by depression till approximately flush with the fixed butts and projecting below the shanks, a cam path to act 25 on the low butts and supplemental cams to act on sliding butts projecting thereabove, the dial having a groove therein to permit said sliding butts to project below the shanks in certain needle positions but to cam them up upon moving to certain other positions.

ALBERT E. PAGE.
